UNITED STATES PATENT OFFICE.

FREDERICK MENZER, OF FLINT, MICHIGAN.

VEHICLE-BODY.

SPECIFICATION forming part of Letters Patent No. 630,724, dated August 8, 1899.

Application filed April 29, 1899. Serial No. 714,981. (No model.)

To all whom it may concern:

Be it known that I, FREDERICK MENZER, of Flint, in the county of Genesee and State of Michigan, have invented a new and Improved 5 Vehicle-Body, of which the following is a full, clear, and exact description.

This invention relates to improvements in vehicle-bodies, such as buggies, sleighs, and cutters; and the object is to provide a body so 10 arranged that it may be easily and quickly changed from a single to a double seated vehicle or from a double to a single seat, and, further, to provide a cover to be placed on the body when a single seat is used, the said 15 cover serving to prevent a backward sliding of the seat and also preventing the entrance of mud or dirt rearward of the seat.

I will describe a vehicle-body embodying my invention and then point out the novel 20 features in the appended claims.

Reference is to be had to the accompanying drawings, forming a part of this specification, in which similar characters of reference indicate corresponding parts in all the figures.

25 Figure 1 is a perspective view of a vehicle-body embodying my invention. Fig. 2 is a sectional side elevation thereof and showing the body with the two seats as in use. Fig. 3 is a similar section, but showing a single 30 seat as in use; and Fig. 4 is a perspective view of a body-cover employed.

The vehicle-body is of box-like construction, having side pieces 1 and a rear end piece 2. Secured to the inner sides of the side pieces 35 1 are guide-strips 3, on which a seat 4 is mounted to slide.

Hinged to a cross-bar 5 in the vehicle-body is a supplementary seat 6, and also hinged to this cross-bar 5 or to the standard at the ends 40 thereof is a back 7 for the seat 6. A brace 8 has the lower ends of its legs pivoted to the bottom of the vehicle-body, and the cross-bar portion of this brace is designed to engage in a slot or recess 9 formed in the bottom of the 45 seat 6 for the purpose of holding said seat 6 in position when used as a seat. When a single-seated vehicle is desired, the brace 8 is moved down to the bottom of the vehicle, so that the seat 6 may swing downward and form 50 a drop for the seat 4 when said seat 4 is moved to its forward position, and at this time the

back 7 will be swung downward into the body underneath the seat 4.

Supporting-pins 10 are connected to the bottom 11 of the vehicle-body and are designed to receive and support the back 7 somewhat above the bottom 11 of the vehicle-body. Attached to the front and ends of the seat 6 is a curtain 12 of any suitable flexible material. This curtain is designed to hide 55 the opening between the seat 6 and the bottom of the vehicle and when said seat 6 is in its seating position. The curtain 12 in its front portion has a V-shaped opening 13, which permits the curtain to be snugly folded 60 when the seat 6 is in its lower position.

When the seat 4 is in its forward position to provide a single-seated vehicle, the portion of the body rearward of said seat is to be covered by means of a cover, here shown as consisting of two sections 14 15, which are arranged together, so that the cover may be folded and placed in the bottom of the vehicle-body when not in use. The sides and rear end of the cover are rabbeted, so as to engage 70 over the tops of the side pieces 1 and the end piece 2 and also against the inner surfaces of said pieces. By this construction the cover will be prevented from moving laterally or rearward. When in position, the cover is to 75 be locked in place by any suitable means. I have here shown a button or latch 16 pivoted to one section of the cover and adapted to engage in a recess formed in the end piece 2, and extended from this latch or button and 80 through the cover is a finger-piece 17. The forward end of the cover is beveled upward and rearward, so as to engage against the corresponding bevel of the back portion of the seat 4, thus preventing an upward movement of the forward end of the cover.

When a two-seated vehicle is desired, the seat 4 is to be slid back, as indicated in Figs. 1 and 2, and of course at this time the cover, consisting of the folding sections, to be placed 95 in the bottom of the vehicle. The seat 6 is then to be raised to its horizontal position and supported by its brace, and at the time of raising the said seat 6 the back 7 is to be moved upward, so that a hook 18 on the back will engage in a recess 19 formed in the bottom of the seat 6 near its rear edge.

Having thus fully described my invention, I claim as new and desire to secure by Letters Patent—

1. A vehicle-body, a main seat movable longitudinally thereof, and a cover designed to be placed on the vehicle-body rearward of the seat, the said cover consisting of flat sections hinged together so as to fold closely together, substantially as specified.
- 10 2. A vehicle-body, a seat mounted to slide on the side pieces of the body, a cover consisting of two hinged sections and having its sides and rear end adapted for engagement upon the top of the side pieces of the body and upon the top of the rear end piece of the body, and also for engaging against the inner sides of the side pieces and end piece, and

means for locking the cover in position, substantially as specified.

- 15 3. A vehicle-body of box-like construction, a main seat mounted to slide on the body, an auxiliary seat having swinging connection with the body, a back for said auxiliary seat, having swinging connection with the body, and pins or posts on the body of the vehicle 25 upon which the swinging back may rest when in its lowered position and holding the back free from the bottom of the body, substantially as specified.

FREDERICK MENZER.
